[57] ABSTRACT

In many propeller type turbines the runner blades are supported in a hollow hub and are pivoted about their axes relative to the hub. The operating mechanism is in many instances contained within the hub. Such operating mechanism frequently requires a pivot pin which is supported in a bore in the hub wall. For ease of manufacture and assembly this bore usually extends completely through the wall of the hub, and a plug is required to seal the end of the bore. A simplified design of such a plug is shown herein wherein an O-ring is utilized to seal the bore and a set screw is threaded into a bore partially in the plug and partially in the hub wall and is tack-welded in place.

PLUG AND SEAL DESIGN FOR ADJUSTABLE BLADE PROPELLER TURBINE

This invention pertains in general to hydraulic turbines and more particularly to hydraulic turbines of the propeller type which utilize adjustable runner blades.

In order to simplify the description, reference will be made hereinafter to an adjustable blade turbine frequently referred to in the industry as a Kaplan turbine. However, it should be understood that the invention is applicable to a propeller turbine wherein the guide vanes are adjusted by means of a mechanism contained within the turbine hub.

The blades of an adjustable blade turbine frequently referred to in the industry as a Kaplan turbine are adjustable so as to obtain the optimum efficiency of the turbine under its entire range of operation. Essentially the turbine runner blades are pivotally supported by a hollow hub from which the blades project uniformly, the hub having suitable bearings which pivotally receive trunnions projecting from the blades. The blades can be varied in pitch simultaneously between predetermined optimum open and closed positions within required limits by the use of an operating mechanism such as a hydraulic servomotor usually contained within the hollow hub or in the turbine shaft.

This operating mechanism is usually in the form of a hydraulic servomotor which is connected to a crank arm on the trunnion of the blades by means of a mechanical linkage. Frequently this mechanical linkage requires a pivot pin which is usually supported in a bore which extends through the outer wall of the turbine hub. After the pin is properly inserted it is necessary to effectively seal the bore so that water passing around the outside of the hub does not enter the interior thereof and also to keep the pressurized oil on the inside of the hub from leaking out.

In the past this bore has been effectively sealed by inserting a plug in the bore and providing a weld between the adjacent surfaces of the plug and the hub. This procedure, although satisfactory, is considerably expensive because of the time involved in providing the weld. Furthermore, in the event that repair is required, the weld had to be removed which also was a time-consuming operation.

It is therefore the general intention and object of this invention to provide a plug for the pivot pin bore of a hydraulic turbine of the hereinbefore described type which can be more easily installed and removed than prior art plugs.

An additional object of the subject invention is to provide a plug for a pivot pin bore of a hydraulic turbine of the hereinbefore described type wherein the liquid seal is provided by an annular sealing element held in a groove provided in either the bore wall or plug surface and the plug is held in place by an engaging member contained in an opening partially in the plug and partially in the hub wall and tack-welded to the hub.

A more specific object of the subject invention is to provide a plug of the hereinbefore described type wherein an annular groove is provided in the plug to receive the annular sealing element and a threaded bore is provided partially in the plug and partially in the hub wall with a set screw turned therein, and the set screw is tack welded in place.

These and other objects of the subject invention will become more fully apparent as the following descrip-

tion is read in light of the attached drawings wherein:

FIG. 1 is a side elevation of a typical Kaplan runner;

5 FIG. 2 is an enlarged section of the prior art plug and seal;

FIG. 3 is an enlarged view of the new design plug and seal;

10 FIG. 4 shows a cross-sectional view of a portion of a Kaplan runner utilizing the subject invention; and

FIG. 5 is a view of the mechanical linkage taken on line V—V of FIG. 4.

15 Referring to the drawings a hollow turbine runner hub is generally indicated as 6. The hollow hub 6 has a plurality of circumferentially spaced blades 7 (herein shown as 4) pivotally connected to the hub. Each blade is provided with a trunnion 8 which extends through a sleeve bearing 9 and terminates in the interior of the hub. The blades extend radially outward from the hub and are acted upon by the water to rotate the runner in the conventional manner generally known in the art.

20 The operating mechanism for oscillating the turbine blades is also contained within the hub 6. As shown herein for purposes of illustration, this operating mechanism includes a reciprocable shaft 11 extending through the hub to a cross-head 12. This cross-head is connected by a mechanical linkage to the blade trunnion.

25 30 The mechanical linkage includes a link bolt 13 connected to the cross-head 12 and a set of links 10 connecting the link bolt to one arm 14 of a bell crank 15. The other arm 16 of the bell crank is in turn connected to connecting links 17 which are attached to a rocker arm 18 connected to the trunnion 8. The bell crank 15 is pivotally supported by a pivot pin 19. One end of this pivot pin is supported in a bore 20 extending through the wall of the hub 6.

35 40 Referring now to FIG. 2, in the prior art design the pivot pin was sealed from the exterior of the hub by means of a plug 21 inserted in the outer end of the bore 20 and held in place by a weld ring 22. A threaded bore 23 was provided in the plug 21 and a threaded insert 24 was then turned into the threaded bore. This insert was again welded to the plug as at 26. It can be seen that this design required considerable time both in application and in the event that removal was necessary.

45 50 Now referring to FIG. 3 the new design includes an annular groove 27 provided in the outer surface of the plug 28. A ring type sealing element herein shown as an O-ring 29 is inserted in the annular groove 27. It should be understood that this annular groove could be provided in the interior surface of the bore rather than the plug. The plug 28 is then inserted in the bore and a threaded opening 31 is drilled and tapped. This opening is received partially in the wall of the hub 6 and the side wall of the plug 28. A set screw 32 is then turned into the threaded bore 31 adequately holding the plug and hub against both rotational and axial relative movement. To insure the set screw stays in the threaded bore a tack weld 33 is provided as shown.

55 60 65 From the above it can be seen that the new design is much simplified in the amount of time required to insert the plug as well as to remove the plug.

The embodiments of the invention in which an exclusive property or privilege is claimed are defined as follows:

1. A hydraulic turbine adapted for operation in a liquid medium having walls defining a hollow runner hub, blades having trunnions mounted for oscillation in said hub, operating means supported within said hub for imparting oscillating movement to said blades, mechanical linkage means connecting said operating means to said blades including a pivot pin supported in a bore extending through said hollow hub wall, and means for sealing said bore from the exterior of said hub comprising; a plug located in said bore between the terminal end of said pivot pin and the outer surface of said hub wall; a sealing ring engaging said plug and said bore wall to provide a liquid tight seal therebetween; walls defining a longitudinally extending opening existing partially in said hub wall and partially in said plug, the

outer end of said opening being open to the exterior of said hub and the inner end presenting blind end walls terminating short of said seal ring; engaging means contained in said opening and engaging both said hub and said plug to prohibit relative rotation therebetween and engaging said end walls to prohibit relative longitudinal movement therebetween; and a tack weld between said engaging means and said hub to hold said engaging means and said plug in place.

10 2. The hydraulic turbine sealing means set forth in claim 1 wherein said opening is a threaded bore and said engaging means is a set screw which prevents both relative rotational and longitudinal movement between said plug and said hub.
